UNITED STATES PATENT OFFICE.

GEORGE SOUER, OF RICE'S, MINNESOTA, ASSIGNOR OF ONE-HALF TO
ELMER M. JOHNSON, OF ST. CLOUD, MINNESOTA.

BLACKSMITH'S FORGE.

SPECIFICATION forming part of Letters Patent No. 642,271, dated January 30, 1900.

Application filed June 5, 1899. Serial No. 719,443. (No model.)

To all whom it may concern:

Be it known that I, GEORGE SOUER, a citizen of the United States, residing at Rice's, in the county of Benton and State of Minnesota, have 5 invented certain new and useful Improvements in Blacksmiths' Forges, of which the following is a specification, reference being had therein to the accompanying drawings.

My invention relates to portable blacksmiths' forges; and the objects of my invention are to produce a simple and inexpensive portable forge the frame of which is adapted to be constructed mainly of wood and to carry a vise and to be connected with a work-bench 15 alongside thereof, the fan-blower of said forge having a vertical shaft and an operating-shaft placed also vertically, with a crank-handle within convenient reach of the smith. I attain these objects by the construction illustrated in the accompanying drawings, in 20 which—

Figure 1 is a perspective view of the forge and work-bench constructed in accordance with my invention. Fig. 2 is a side view of 25 the forge. Fig. 3 is a longitudinal vertical section of the same. Fig. 4 is a horizontal section taken above the hearth of the forge. Fig. 5 is a perspective view of the blast-directing hood and grate thereon.

30 In said drawings, A represents the rectangular top frame of the forge, which is supported by four uprights or legs B B², which are united together about half-way of their height by another rectangular frame A². Between the uprights B² is placed the casing for the fan D. Said casing consists, preferably, of tongue-and-groove boards secured horizontally to the top frame A to constitute the top a of the casing and of a floor a², secured to the 35 frame A², and through said floor there is an opening a³, constituting the eye of the fan-case. One end of said fan-case is semicylindrical, as shown at a⁴, while its inner end is made acute by an inclined partition E to properly direct the air-blast upwardly toward the 40 grate g and hearth h and another inclined partition F, having its lower end converging toward the partition E. Said partition F has a large opening f in the central portion of its

front end, which is covered by a blast-directing hood G, of metal, the flanged edges of which are secured on top of the inclined partition F. The front portion of the top of the hood has the grate g secured thereto over an opening made therein for the passage of the 55 air-blast.

To form the hearth h of the forge and protect the lumber of which the frame is preferably made, a bed of clay H is packed on top of the fan-casing a, on top of the hood G and 60 on top of the inclined partition E. Under said partition a tool-chamber I is provided, having vertical walls i i² and an end door i³. The wall i² provides a bracing-support for the partition E. The lower portion of said partition can thus be made independent of its 65 upper portion and be temporarily slid side- 70 wise for the escape of clinkers or be perforated and provided with a slidable register-plate e, placed thereon.

The shaft d of the fan is vertical and guided in suitable bearings secured to the frame. The upper end of said shaft carries a pinion k, which meshes with a gear-wheel L. Said wheel is mounted upon the lower portion of 75 a shaft M, which is guided in a vertical position in bearings n, secured to the frame. The upper end of the shaft M carries a crank-handle m in convenient position to be operated by the smith while attending to an article in 80 the fire.

To one of the legs B² is secured a vise P, having an adjustable jaw p in connection with said leg. The legs B² also constitute an end support for a bench Q, the other end of which 85 is secured by legs q, properly steadied to the bench by lateral braces r, said bench adding to convenience of the forge by furnishing a handy and elevated support for some of the materials used by the smith.

Having now fully described my invention, 90 I claim—

A blacksmith's forge consisting of a rectangular upper frame a rectangular under frame, and between them a fan-case in one end, said 95 fan-case having an upwardly-inclined air-passage consisting of two converging partitions, the upper partition having an air-passage, a

tapering hood G over said passage and a grate upon said hood, a hearth consisting of clay packed within the upper frame and resting upon a portion of the fan-case and hood, a fan 5 within said case, said fan having a vertical shaft, a pinion on the upper end of said shaft, a horizontally-mounted gear-wheel meshing with said pinion, and a vertically-retained

crank-shaft secured to said gear-wheel, substantially as described.

In testimony whereof I affix my signature in presence of two witnesses.

GEORGE SOUER.
